UNITED STATES PATENT OFFICE

168,967

PROPORTIONAL DIVIDER

Leonard Z. Plebanek, Chicago, Ill.

Application May 19, 1952, Serial No. 19,780

Term of patent 3½ years

(Cl. D52—1)

To all whom it may concern:

Be it known that I, Leonard Z. Plebanek, a citizen of the United States, residing at Chicago, in the county of Cook and State of Illinois, have invented a new, original, and ornamental Design for Proportional Dividers, of which the following is a specification, reference being had to the accompanying drawing, forming a part thereof.

Fig. 1 is an elevational view of one side of the proportional dividers, showing my new design;

Fig. 2 is an edge elevational view of the same;

Fig. 3 is an elevational view of the other side of the proportional dividers; and

Fig. 4 is a fragmentary elevational view with the screw head omitted.

I claim:

The ornamental design for a proportional divider, as shown.

LEONARD Z. PLEBANEK.
